UNITED STATES PATENT OFFICE.

GEORGE F. PAWLING, OF PHILADELPHIA, PENNSYLVANIA.

MEANS OF SUPPORTING CEILING FURRING.

Application filed November 26, 1924. Serial No. 752,286.

This invention, generally stated, relates to building construction, especially concrete structures and has more especial relation to a ceiling structure and manner of attaching furring to its supports.

As at present practiced, it is the accepted custom to wire furring to the supporting structure in the construction of a ceiling of concrete, which not only consumes considerable time, is more or less expensive, and requires the services of skilled workmen. Further from an engineering view-point this procedure is not especially desirable.

The leading object of the present invention is to overcome the above disadvantageous features and provide an efficient, practical and inexpensive system of ceiling furring attachment to its supports which may be applied expeditiously and by unskilled workmen. A further object resides in the provision of a clip of simple and inexpensive construction, which may be conveniently used for effecting the results sought by said leading object. Other and further objects not at this time appearing will be hereinafter more specifically referred to.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in side elevation illustrating one way of attaching ceiling furring to joist in accordance with the present invention.

Fig. 2, is an end view of Fig. 1.

Fig. 3, is a perspective view of one form of clip employed.

Fig. 4, is a view end of another manner of attaching ceiling furring to joist, and

Fig. 5, is a perspective view of the type of clip shown in Fig. 4.

For the purpose of illustrating my invention I have shown in the accompanying drawings two forms thereof which are at present preferred by me, since the same have been found in practice to give satisfactory and reliable results, although it is to be understood that the various instrumentalities of which my invention consists can be variously arranged and organized and that my invention is not limited to the precise ar-

rangement and organization of the instrumentalities as herein shown and described.

Referring to the drawings in detail and with more especial relation to Figs. 1 to 3 the supporting structure, which in the present instance comprises bar-joist 1, has positioned therebelow sectional, ceiling furring designated 2, and which is of U-shaped cross-section. Ordinarily such furring is secured to the bar-joist by means of wire. According to the present invention I provide a plurality of clips, see Fig. 3, by the use of which I am enabled to attach the furring to the bar-joist more expeditiously, cheaply and in a more thorough manner from an engineering view-point and by unskilled workmen.

The clip is made from a single piece of wire and is bent to provide an inclined loop 3, vertical side pieces 4 and a pair of horizontal supporting arms 5, terminating in upturned fingers 6. In use the loop 3 is positioned upon a lower horizontal rail 7 of the bar-joist 1, so that the side pieces 4 straddle the said rail, the furring being arranged upon the supporting arms 5, with the fingers 6 paralleling one vertical wall of the furring and the side pieces 4 paralleling the opposite wall of the furring. An unskilled workman may thus readily and rapidly attach furring to bar-joist. It is of course understood that the bar-joist is spaced in accordance with building regulations and that the furring is suspended at desired intervals.

Metal lath, expanded metal or equivalent material of any desired type is then attached to the furring in any desired manner, although in order to provide a good job from an engineering view-point I prefer to employ the form of furring shown in my co-pending application for patent Serial No. 736,245, filed September 6, 1924 and attach thereto metal lath of the type shown in my co-pending application for patent Serial No. 723,638, filed July 2, 1924. The object of having the loop 3 of my clip inclined is to have the center of gravity as nearly over the longitudinal axis of the furring as possible in order to prevent tilting of parts.

In Figs. 4 and 5, I have shown a slightly different form of joist, commonly called steel-joist, and which is designated 7. The principal of applying the furring 8 is the same except that a slightly different form of clip is employed. A relatively U-shaped clip is used having a lower cross-bar 9 to

support the furring and having vertical arms 10 terminating in hook-like fingers 11 for engaging over the flanged part 12 of the steel-joist. The manner of applying metal lath or the like may be the same as above recited.

It will now be apparent that I have devised a novel and useful construction which embodies the features of advantage enumerated as desirable in the statement of the invention and the above description and while I have in the present instance shown and described the preferred embodiments thereof which have been found in practice to give satisfactory and reliable results, it is to be understood that the same are susceptible of modification in various particulars without departing from the spirit or scope of the

invention or sacrificing any of its advantages.

20

What I claim is:

A clip for securing furring to skeletonized joist formed from a single piece of material, as wire, and bent to form a horizontal, furring supporting portion and a pair of vertical side pieces terminating in a loop projecting at an inclination and in a direction toward the toe of the clip, said loop being adapted to engage over a bar of the lower cord of skeletonized joist and an upturned end for each of said horizontal portions which upturned parts form the toe of the clip.

In testimony whereof, I have hereunto signed my name.

GEO. F. PAWLING.
